UNITED STATES PATENT OFFICE.

ERNEST FRASER JONES, OF JOHANNESBURG, TRANSVAAL, SOUTH AFRICA, ASSIGNEE,
BY MESNE ASSIGNMENTS, TO DEMAG AKTIENGESELLSCHAFT, OF DUISBURG, GERMANY.

HAMMER DRILL.

Application filed October 8, 1925, Serial No. 61,251, and in the Union of South Africa December 18, 1924.

The present invention relates to hammer rock drills of the kind in which the hammer piston has a forwardly extending nose, a portion of which is fluted or of non-cylindrical section and engages the similarly shaped bore of the tool chuck for rotating the latter.

The principal purpose of the invention is to provide a construction which can attain the known advantages of an effective air seal between the piston nose and the front cylinder cover, without requiring the piston nose to be lengthened for the purpose of so sealing it.

15 In the accompanying drawings—

Fig. I shows a longitudinal section of the forward portion of such a drill constructed according to the invention, the hammer piston being shown at the forward end of its stroke.

20 Fig. II is a cross section on II, II Fig. I.

Fig. III is similar to Fig. I but shows the hammer piston at the rear of its stroke.

25 Fig. IV is similar to the right hand portion of Fig. I, but showing a piston nose of different form.

Fig. V is a cross section on V, V Fig. IV.

30 2 is the drill cylinder in which the head 3 of the hammer piston reciprocates. The nose 4, 5 of the piston extends through the front cylinder cover 6 and into the chuck 7 to strike the drill tool 8.

The piston is rotated by any suitable means. It transmits its rotational movement to the chuck 7 which in turn rotates the tool 8. For thus transmitting rotational movement, the piston nose and the chuck are made of non-cylindrical form such as to engage one another for rotation whilst being free 40 for relative reciprocating movement. Usually the internal surface of the chuck is fluted as indicated at 9 and corresponding fluting 5 is formed on the piston nose. In some cases however polygonal forms are employed, instead of the fluting, as illustrated in Figs. IV and V.

50 It was formerly the practice to allow the fluted portion 5 of the piston nose to enter the cylinder during the rearward stroke of the piston; and piston lengths and weights were based on this arrangement. Later, in order to prevent air from passing from the cylinder along the flutes, the construction was so modified that the flutes did not enter the

cylinder. This was effected by providing the 55 piston nose with a plain cylindrical surface 4, at least equal in length to the piston stroke, which surface formed an air seal with a surrounding member situated between the cylinder and the chuck cavity 10. Said plain 60 cylindrical surface 4 was usually formed in the position illustrated viz, between the piston head 3 and the fluting 5, in which case it sealed with the cylinder cover 6. The piston 65 nose thus comprised a plain cylindrical portion and a fluted portion, each at least equal in length to the piston stroke; and as a consequence the length and weight of the piston were increased as compared with the length 70 and weight of a corresponding standard piston of which the flutes entered the cylinder.

The present invention provides an improved construction which enables the cylindrical portion 4 of the piston nose to maintain an air seal with the cover 6, without the necessity of lengthening the piston and the 75 drill in which it works as compared with the standard short piston above referred to.

To this end the piston nose is made, as in the prior sealing arrangement, with a rear 80 cylindrical portion 4 and a forward non-cylindrical portion 5. In previous constructions, however, the non-cylindrical portion was cut into the nose; but according to the present invention said non-cylindrical portion 85 is made of such greater diameter than the rear cylindrical portion, that the corresponding fluting 9 (or equivalent formation) of the chuck is everywhere of greater internal diametral dimensions than the diameter of the plain cylindrical portion 4. That is to say, in the fluted construction the ribs 11 stand out from the piston nose.

This arrangement enables the plain portion 4 of the nose to overlap the fluting 9 of 90 the chuck, as shown in Fig. I. Accordingly the rear end 12 of the chuck fluting may be positioned as near to the cylinder 2 as desired or as is usual with "short" pistons whilst permitting the plain cylindrical portion 4 of the piston to be long enough to remain throughout the piston stroke in sealing 95 engagement with the front cylinder cover 6. Moreover, by making the fluted portion 5 of the piston nose of short length relatively to the piston stroke, the chuck fluting 9 may be 100 of the ordinary length required by the piston stroke, whilst the whole piston may be made 105

of substantially the same length as the "short" piston. If the plain portion 4 of the piston nose is made of the usual diameter, the increased diameter of the fluted portion 5 tends to compensate for the loss of area of the piston flutes due to their being shortened.

Figs. IV and V illustrate the application of the invention to the case in which the chuck engaging portion of the piston nose and the chuck bore are of hexagonal or other polygonal form; the polygon being made of such size that its inscribed circle is of greater diameter than the plain cylindrical portion of the chuck nose.

To enable the piston to be put into position, the cylinder cover 6 may be made in halves, having ground jointing surfaces 13, and held together by a ring 14.

I claim:—

1. In a hammer rock drill the combination of a cylinder; a cylinder front cover having an aperture therein; a hammer piston reciprocating and rotating in the cylinder and provided with a nose extending forwardly through the aperture in the cylinder cover in air-retaining relation and adapted to strike a drill tool, the rear end of the nose having a plain cylindrical surface which operates through the aperture of the front cover and remains therein in all positions of the piston and the forward end of the nose being of non-circular section of greater radial extent than the plain cylindrical surface; and a rotatable chuck adapted to receive a drill tool and to engage the same for rotation and having a non-circular bore of corresponding form to the non-circular forward end of the hammer piston and slidably engaged by said non-circular end whereby the piston rotates the chuck and, through it, the drill tool, while being free to reciprocate relatively to the chuck.

2. In a hammer rock drill the combination of a cylinder; a cylinder front cover having an aperture therein; a hammer piston reciprocating and rotating in the cylinder and provided with a nose extending forwardly through the aperture in the cylinder cover in air-retaining relation and adapted to strike a drill tool, the rear end of the nose having a plain cylindrical surface which operates through the aperture of the front cover and remains therein in all positions of the piston, and the forward end of the nose being of non-circular section of greater radial extent than the plain cylindrical surface; and a rotatable chuck adapted to receive a drill tool and to engage the same for rotation, said chuck having a non-circular bore of corresponding form to the non-circular forward end of the hammer piston and slidably engaged by said non-circular end whereby the piston rotates the chuck and, through it, the drill tool, while being free to reciprocate relatively to the chuck, the chuck bore being of greater diameter than the plain cylindrical portion of the piston nose and overlapping the same when the piston is at the forward end of its stroke.

the plain cylindrical portion of the piston nose whereby said plain cylindrical portion can enter said bore during the reciprocation of the piston.

3. In a hammer rock drill the combination of a cylinder; a cylinder front cover having an aperture therein; a hammer piston reciprocating and rotating in the cylinder and provided with a nose extending forwardly through the aperture in the cylinder cover in air-retaining relation and adapted to strike a drill tool, the rear end of the nose having a plain cylindrical surface which operates through the aperture of the front cover and remains therein in all positions of the piston, and the forward end of the nose being of non-circular section of greater radial extent than the plain cylindrical surface; and a rotatable chuck adapted to receive a drill tool and to engage the same for rotation, said chuck having a non-circular bore of corresponding form to the non-circular forward end of the hammer piston and slidably engaged by said non-circular end whereby the piston rotates the chuck and, through it, the drill tool, while being free to reciprocate relatively to the chuck, the chuck bore being of greater diameter than the plain cylindrical portion of the piston nose whereby said plain cylindrical portion can enter said bore during the reciprocation of the piston, and the rear end of the non-circular chuck bore being distant from the cylinder front cover by less than the length of the piston stroke.

4. In a hammer rock drill the combination of a cylinder; a cylinder cover having an aperture therein; a hammer piston reciprocating and rotating in the cylinder and provided with a nose extending forwardly through the aperture in the cylinder cover in air-retaining relation and adapted to strike a drill tool, the rear end of the nose having a plain cylindrical surface which operates through the aperture of the front cover and remains therein in all positions of the piston, and the forward end of the nose being of non-circular section of greater radial extent than the plain cylindrical surface; and a rotatable chuck adapted to receive a drill tool and to engage the same for rotation, said chuck having a non-circular bore of corresponding form to the non-circular forward end of the hammer piston and slidably engaged by said non-circular end whereby the piston rotates the chuck and, through it, the drill tool, while being free to reciprocate relatively to the chuck, and the chuck bore being everywhere of greater diameter than the plain cylindrical portion of the piston nose and overlapping the same when the piston is at the forward end of its stroke.

5. In a hammer rock drill the combination of a cylinder; a cylinder front cover having an aperture therein; a hammer piston reciprocating and rotating in the cylinder

and provided with a nose extending forward-
ly through the aperture in the cylinder cover
in air-retaining relation and adapted to strike
a drill tool, the rear end of the nose having a
5 plain cylindrical surface which operates
through the aperture of the front cover and
remains therein in all positions of the piston,
and the forward end of the nose being of non-
circular section of greater radial extent than
10 the plain cylindrical surface; and a rotatable
chuck adapted to receive a drill tool and to
engage the same for rotation, said chuck hav-
ing a non-circular bore of corresponding form

to the non-circular forward end of the ham-
mer piston and slidably engaged by said non-
circular end whereby the piston rotates the
chuck and, through it, the drill tool, while be-
ing free to reciprocate relatively to the chuck,
the plain cylindrical surface of the nose and
the non-circular chuck bore being each at 15
least as long as the piston stroke, and the non-
circular forward end of the piston nose being
substantially shorter than said chuck bore.
20

In testimony whereof I affix my signature.

ERNEST FRASER JONES.
